[57] CLAIM

The ornamental design for a hopper for grass cuttings,
as shown and described.

DESCRIPTION

FIG. 1 is a left side elevational view of a hopper for
grass cuttings showing my new design;

FIG. 2 is a right side elevational view thereof;

FIG. 3 is a front elevational view thereof;

FIG. 4 is a rear elevational view thereof;

FIG. 5 is a top plan view thereof; and,

FIG. 6 is a bottom plan view thereof.

The broken lines shown in FIGS. 1 through 6 of the
drawing are for illustrative purposes only and form no
part of the claimed design.
